UNITED STATES PATENT OFFICE.

J. R. ROBINSON, OF BOSTON, MASSACHUSETTS.

STEAM-BOILER FURNACE.

Specification of Letters Patent No. 32,313, dated May 14, 1861.

To all whom it may concern:

Be it known that I, J. R. ROBINSON, of Boston, in the county of Suffolk and State of Massachusetts, have invented a new and useful Improvement in Steam-Boiler Furnaces; and I do hereby declare that the following is a full, clear, and exact description of the same, reference being had to the accompanying drawings, making part of this specification, in which—

Figure 1, is a longitudinal vertical section of a boiler with my improvement. Fig. 2, is a transverse vertical section of the same in the line x, x , of Fig. 1. Fig. 3, is a transverse vertical section of the same in the line y, y , of Fig. 1.

Similar letters of reference indicate corresponding parts in the several figures.

This invention relates to the employment of a gas-mixing chamber arranged in rear of the fire-chamber, between the latter and the flue or flues or tubes of the boiler. It consists in a certain construction and arrangement of two walls separating the two chambers and a certain novel system of passages in said walls, whereby the mixture of the gases of combustion and the air which leaves the fire-chamber in an uncombined state is caused to be partly effected in their passage through and between said walls and to be completed in a very perfect manner in the mixing-chamber.

To enable others skilled in the art to make and use my invention, I will proceed to describe its construction and operation.

The boiler represented in the drawing is of the horizontal multi-tubular kind. The inner part a, b, c , corresponds in its construction with the fire box of an ordinary locomotive boiler but is made of much greater length in order that the fire chamber A, and gas-mixing-chamber B, may be included within it.

C and D, are the two walls which separate the fire-chamber from the gas-mixing-chamber and which with their passages constitute my invention. These walls are arranged at a short distance apart and both extend all across the inner portion a, b, c , of the boiler in rear of the fire grate G, and have an upright space or chamber E, between them. The rear wall C, extends up to the top of the inner portion a, b, c , of the boiler, but the front wall D not so high. The front wall D, has a passage d, through it, forming a communication between the fire-chamber

and the chamber E, the said passage extending nearly all across the wall as shown in Fig. 2, and its bottom being about the height of the top of an ordinary fire bridge. The 60 space between the walls C, and D, is partly closed at the top by a cover F, but in this cover there is a passage f, fitted with sliding valves g, g, of fire brick. Between this cover F, and the top of the inner part a, b, c , of 65 the boiler, there is a space H, of considerable depth. The back wall C, has passages e, e, through its lower part one at each side commencing about, or a little above half way up, and extending downward obliquely toward 70 the center so as to nearly meet at the bottom as shown in Fig. 3, but instead of these passages, several smaller passages may be provided in the lower part of the wall C, as the equivalents of e, e; or a number of smaller 75 passages may be provided as well as the larger passages e, e.

The greater portion of the gases of combustion and uncombined air pass from the fire box A, through the passage d, into the 80 chamber E, between the walls C, D, but the lighter gases which ascend to the upper part of the fire-chamber above the top of the passage d, are drawn into the space H, and caused to pass through the passage f, into 85 the chamber E, and on their entrance into the said chamber meet the gases and air entering through d, and all pass together down the chamber E, becoming partly mixed on their way, and from thence pass through the 90 passages e, e, into the lower part of the mixing-chamber B, rolling around the inner edges of the said passages with an eddy-like movement. The portions entering the passages e, e, meet in the middle of the lower 95 part of the mixing-chamber B, and as they rise with their rolling or eddy-like movement continued, the whole of the gases and air become so perfectly mixed that a perfect combination and combustion is effected. 100

In some cases it might for some reasons not be desired to have the means I have described for collecting and conveying away the lighter gases from the upper part of the fire-chamber, and in such cases the cover F, 105 of the chamber E, might be dispensed with, and the front wall D, be carried no higher than where the bottom of the passage d, is now represented. The opening between the top of the wall D, and the top of the box 110 a, b, c , will then be the equivalent of the passage d. I prefer however always to use the

separate passages *f*, *f*, for the lighter gases whenever practicable.

h, *h*, are passages provided in the lower part of the wall C, D, F, to allow ashes and dirt to be raked from the bottom of the gas-mixing-chamber B, into the ash pit, the bottom of which is on a level, or nearly so with the bottom of the said chamber. These passages are fitted with flap doors *i*, *i*, which are only opened to rake the ashes and dirt through the said passages.

Two walls of precisely similar construction and with a similar system of passages may be used in the setting of cylindrical or other boilers having no fire boxes within them, the side walls of the setting, in such case forming the sides of the fire-chamber, and gas-mixing-chamber, and the wall C, being carried up close to the bottom of the boiler. When in such application of my invention it is desired to have separate means of exit for the lighter gases from the fire-

chamber, two passages like *f*, *f*, one near each side of the chamber will be required, owing to the highest portions of the chambers A, and B, being at the sides and above the lowest portion of the boiler.

What I claim as my invention and desire to secure by Letters Patent, is,—

1. The two walls C, D, and their interposed chamber E, and passages *d*, *e*, *e*, constructed and arranged between the fire chamber A and gas-mixing chamber B, substantially as and for the purpose herein specified.

2. In combination with the said walls, interposed chamber, and passages, the within described arrangement of the passage or passages *f*, for the purpose specified.

J. R. ROBINSON.
